COVER FOR CONTAINERS, JARS, ETC.

Souren Kazanjian, Woodside, N. Y.

Application June 10, 1939, Serial No. 278,394

8 Claims. (Cl. 215—88)

This invention relates to new and useful improvements in covers for containers, jars, etc., and has particular reference to a construction which permits the cover to be pressed closed 5 tightly.

More specifically, the invention proposes a cover as mentioned which is characterized by a hollow body having a top wall portion continuing into a skirt portion formed with threads for 10 threadedly engaging upon the neck of a container, jar or the like, and a novel construction of rigid member, sealing element and screw for accomplishing the press tight arrangement previously referred to.

More specifically the invention proposes that 15 the screw be threadedly engaged through the top wall portion of the cover and abut against the rigid member which in turn will press the sealing element upon the edge of the neck of the container for producing the tight arrangement previously described.

Still further it is proposed to provide two sealing elements. One arranged to be pressed against 20 the edge of the neck of the container and the other to be simultaneously pressed against the edge of the neck of the container and the skirt portion of the cover body.

Still further the invention proposes the construction of a cover as mentioned which is simple 25 and durable and which may be manufactured and sold at a reasonable cost.

For further comprehension of the invention, and of the objects and advantages thereof, reference will be had to the following description and 30 accompanying drawing, and to the appended claims in which the various novel features of the invention are more particularly set forth.

In the accompanying drawing forming a material part of this disclosure:

Fig. 1 is a vertical sectional view of the press 35 tight cover constructed according to this invention and shown mounted upon the neck of a container or jar.

Fig. 2 is an enlarged detailed view of the top 40 portion of Fig. 1.

Fig. 3 is an elevational view looking in the direction of the line 3—3 of Fig. 2.

Fig. 4 is a horizontal sectional view taken on 45 the line 4—4 of Fig. 2.

The press tight cover for containers, jars and the like, according to this invention, includes a hollow cover body 21 having the top wall 21^a and a skirt 21^b. A sealing element 22 is mounted 50 within the cover body and has a face portion

22^a engaging the inner face of the skirt wall 21^b and another face wall 22^b which engages the top edge of the neck 23 of the container or the like. An auxiliary sealing member 24 extends through 5 an opening in the sealing element 22 and also engages the edge of the neck 23.

A rigid element 25 has a beveled portion 25^a which engages against a complementary beveled portion 22^c upon the sealing element 22. The arrangement is such that when the rigid element 25 is forced outwards because of the contacting beveled surfaces, the sealing element 22 will be simultaneously urged against the inside 10 face of the skirt portion 21^b and against the edge 15 of the neck 23.

An arrangement is provided for lifting the rigid element 25 outwards when desired. This arrangement includes the screw 26 threadedly engaged through the top wall 21^a and provided at 20 its inner end with a flange portion 27. This flange portion is rotatively connected with the rigid element 25. The rotative connection is accomplished by the flange 27 engaging into a recess 25 formed in the rigid element 25 and rotatively held in this recess by an annular member 28 mounted upon the rigid element 25 and partially extended over the recess. The screw 16 is provided with a head 29 upon its outer end by which it may readily be turned.

An auxiliary rigid element 30 is superimposed 30 on the auxiliary sealing element 24 and is adapted to move outwards to press the auxiliary sealing element against the edge of the neck of the container 23. More specifically the auxiliary rigid member 30 is disposed within a recess 31 formed in the bottom of the rigid element 25. These rigid elements are loosely connected together by several pins 32 mounted upon one of the elements and engaging in openings 33 formed in the other of the elements. These pins and grooves are arranged to permit slight axial movement of the rigid elements relative to each other. The auxiliary screw 34 threadedly engages through the screw 26 and passes through an opening 35 in 40 the rigid element 25 and abuts against the top 45 of the auxiliary rigid element 30.

The top portion of the outside face of the skirt portion 21^b of the cover body 21 is provided with serrations facilitating the gripping of the body 21 50 when it is desired to engage and remove the body from the neck 23.

The operation of this form of the invention is as follows:

When the screws 29 and 34 are tightly screwed 55

down the rigid elements 25 and 30 will clamp the sealing elements 22 and 24 tightly against the neck 23. Furthermore the sealing element 22 will also be tightly clamped against the inner face of the skirt portion 21^b of the cover body. This serves to assist in locking the cover body 21 against being unscrewed. Furthermore the neck 23 will be tightly sealed by the sealing elements.

10 To remove the cover it is necessary that the screws 26 and 34 be loosened. This releases the pressure upon the sealing elements 22 and 24. Then the cover body 21 may be screwed off of the neck of the container.

15 While I have illustrated and described the preferred embodiment of my invention, it is to be understood that I do not limit myself to the precise construction herein disclosed and the right is reserved to all changes and modifications coming 20 within the scope of the invention as defined in the appended claims.

Having thus described my invention, what I claim as new, and desire to secure by United States Letters Patent is:

25 1. A press tight cover for containers, jars and the like, comprising a hollow cover body having a top wall portion continuing into a skirt portion formed with threads for threadedly engaging upon the neck of a container, jar or the like, a 30 transverse rigid member within said cover body and adjacent said top wall, a sealing element upon the outer face of said rigid member for engaging the edge of the neck of said container, a screw threadedly engaged through said top wall 35 and abutting said rigid member for clamping said sealing element upon said neck when said cover body is mounted on said container, said sealing element having a beveled top portion, said rigid member having a beveled portion engaging said beveled top portion for forcing said sealing element laterally against said skirt portion and down upon the edge of said neck, an auxiliary sealing element extended through an opening in said sealing element and engaging the edge of the neck of said container, an auxiliary rigid element 40 on said auxiliary sealing element, and an auxiliary screw threadedly engaged through said screw and abutting said auxiliary rigid member for 45 clamping the auxiliary sealing element upon said neck portion.

50 2. A press tight cover for containers, jars and the like, comprising a hollow cover body having a top wall portion continuing into a skirt portion formed with threads for engaging upon the neck 55 of a container, jar or the like, a circular sealing element mounted in said cover and having a beveled inner wall, a transverse rigid member disposed within said sealing element and having a beveled peripheral wall engaging said beveled inner wall, means on said cover for moving said rigid member to cause said bevels to ride one on the other to force said sealing element laterally against said skirt portion and down upon the edge of said neck, an auxiliary rigid member disposed within a recess formed in the bottom face 60 of said rigid member, an auxiliary sealing element disposed beneath said auxiliary rigid member, and an auxiliary means on said cover for urging said auxiliary rigid member outwards relative to 65 said rigid member to also force said auxiliary sealing element down on said neck.

70 3. A press tight cover for containers, jars and the like, comprising a hollow cover body having a top wall portion continuing into a skirt portion 75 formed with threads for engaging upon the neck

of a container, jar or the like, a circular sealing element mounted in said cover and having a beveled inner wall, a transverse rigid member disposed within said sealing element and having a beveled peripheral wall engaging said beveled inner wall, means on said cover for moving said rigid member to cause said bevels to ride one on the other to force said sealing element laterally against said skirt portion and down upon the edge of said neck, an auxiliary rigid member disposed within a recess formed in the bottom face 10 of said rigid member, an auxiliary sealing element disposed beneath said auxiliary rigid member, and an auxiliary means on said cover for urging said auxiliary rigid member outwards relative to said rigid member to also force said auxiliary sealing element down on said neck, said means, comprising a tubular screw rotatably extended coaxially through said cover and bearing against the top face of said rigid member. 15

4. A press tight cover for containers, jars and the like, comprising a hollow cover body having a top wall portion continuing into a skirt portion formed with threads for engaging upon the neck of a container, jar or the like, a circular sealing element mounted in said cover and having a beveled inner wall, a transverse rigid member disposed within said sealing element and having a beveled peripheral wall engaging said beveled inner wall, means on said cover for moving said rigid member to cause said bevels to ride one on the other to force said sealing element laterally against said skirt portion and down upon the edge of said neck, an auxiliary rigid member disposed within a recess formed in the bottom face 25 of said rigid member, an auxiliary sealing element disposed beneath said auxiliary rigid member, and an auxiliary means on said cover for urging said auxiliary rigid member outwards relative to said rigid member to also force said auxiliary sealing element down on said neck, said means, comprising a tubular screw rotatably extended coaxially through said cover and bearing against the top face of said rigid member. 30

35

40 5. A press tight cover for containers, jars and the like, comprising a hollow cover body having a top wall portion continuing into a skirt portion formed with threads for engaging upon the neck 50 of a container, jar or the like, a circular sealing element mounted in said cover and having a beveled inner wall, a transverse rigid member disposed within said sealing element and having a beveled peripheral wall engaging said beveled inner wall, means on said cover for moving said rigid member to cause said bevels to ride one on the other to force said sealing element laterally against said skirt portion and down upon the edge of said neck, an auxiliary rigid member disposed within a recess formed in the bottom face 55 of said rigid member, an auxiliary sealing element disposed beneath said auxiliary rigid member, and an auxiliary means on said cover for urging said auxiliary rigid member outwards relative to said rigid member to also force said auxiliary sealing element down on said neck, said means, comprising a tubular screw rotatably extended coaxially through said cover and bearing against the top face of said rigid member, and means for rotatively attaching the bottom of said tubular screw to the top face of said rigid member. 60

65

70

75

and engaging into a recess formed in the top face of said rigid member, and an annular member having its outer edge portion securely attached to said rigid member and its inner edge portion overlying the edge of said flange for rotatively retaining said flange in position within said recess.

6. A press tight cover for containers, jars and the like, comprising a hollow cover body having a top wall portion continuing into a skirt portion formed with threads for engaging upon the neck of a container, jar or the like, a circular sealing element mounted in said cover and having a beveled inner wall, a transverse rigid member disposed within said sealing element and having a beveled peripheral wall engaging said beveled inner wall, means on said cover for moving said rigid member to cause said bevels to ride one on the other to force said sealing element laterally against said skirt portion and down upon the edge of said neck, an auxiliary rigid member disposed within a recess formed in the bottom face of said rigid member, an auxiliary sealing element disposed beneath said auxiliary rigid member, and an auxiliary means on said cover for urging said auxiliary rigid member outwards relative to said rigid member to also force said auxiliary sealing element down on said neck, said means, comprising a tubular screw rotatively extended coaxially through said cover and bearing against the top face of said rigid member, said auxiliary means, comprising a screw coaxially threaded through said tubular screw and having its bottom end extended through an enlarged opening formed in said rigid member and bearing against the top face of said auxiliary rigid member.

7. A press tight cover for containers, jars and the like, comprising a hollow cover body having a top wall portion continuing into a skirt portion formed with threads for engaging upon the neck of a container, jar or the like, a circular sealing element mounted in said cover and having a beveled inner wall, a transverse rigid member disposed within said sealing element and having a beveled peripheral wall engaging said beveled inner wall, means on said cover for moving said rigid member to cause said bevels to ride one on the other to force said sealing element laterally against said skirt portion and down upon the edge of said neck, an auxiliary rigid member disposed within a recess formed in the bottom face of said rigid member, an auxiliary sealing element disposed beneath said auxiliary rigid member, and an auxiliary means on said cover for urging said auxiliary rigid member outwards relative to said rigid member to also force said auxiliary sealing element down on said neck, and means for preventing said auxiliary rigid member from becoming disengaged from the recess in said rigid member while permitting relative movement therebetween.

8. A press tight cover for containers, jars and the like, comprising a hollow cover body having a top wall portion continuing into a skirt portion formed with threads for engaging upon the neck of a container, jar or the like, a circular sealing element mounted in said cover and having a beveled inner wall, a transverse rigid member disposed within said sealing element and having a beveled peripheral wall engaging said beveled inner wall, means on said cover for moving said rigid member to cause said bevels to ride one on the other to force said sealing element laterally against said skirt portion and down upon the edge of said neck, an auxiliary rigid member disposed within a recess formed in the bottom face of said rigid member, an auxiliary sealing element disposed beneath said auxiliary rigid member, and an auxiliary means on said cover for urging said auxiliary rigid member outwards relative to said rigid member to also force said auxiliary sealing element down on said neck, and means for preventing said auxiliary rigid member from becoming disengaged from the recess in said rigid member while permitting relative movement therebetween, said latter-mentioned means, comprising pins mounted on one of said rigid members and engaging vertically arranged slots formed in the other of said rigid members.

SOUREN KAZANJIAN.
